UNITED STATES PATENT OFFICE.

WARD S. IRELAND, OF DALLAS, TEXAS.

TYPE-WRITING MACHINE.

980,274.

Specification of Letters Patent.

Patented Jan. 3, 1911.

Application filed April 5, 1910. Serial No. 553,436.

To all whom it may concern:

Be it known that I, WARD S. IRELAND, of Dallas, in the county of Dallas and State of Texas, have invented certain new and useful improvements in Type-Writing Machines; and I do hereby declare the following to be a full, clear, and exact description of the invention, such as will enable others skilled in the art to which it appertains to make 10 and use the same.

This invention relates to improvements in typewriting machines such as are particularly adaptable for stenographic writing.

The object of my present invention is to 15 so construct a typewriting machine of the character specified that the noise created by the operation of the machine will be reduced to a minimum.

A further object is to construct the writing 20 mechanism in such manner that the ends of the type-bars to which the type are secured shall be caused to move a very slight distance in their coöperation with the platen and still have adequate force applied thereto 25 to effect clear impressions upon the paper and without the necessity of applying excessive pressure upon the keys, or depressing them more than a very limited distance.

With these objects in view the invention 30 consists in certain novel features of construction and combinations of parts as herein-after set forth and pointed out in the claims.

In the accompanying drawings, Figure 1 is a longitudinal sectional view of a portion 35 of a typewriting machine showing an embodiment of my invention. Fig. 2 is a plan view of the same, and Fig. 3 is a detail view.

1 represents the frame of the machine, between the sides of which a bar 2 is secured 40 in the lower intermediate portion of the machine. This bar is widened somewhat at its intermediate portion and provided with a series of parallel fingers 3 forming slots 4 between them for the accommodation 45 of key-bars 5,—the latter being provided at their rear ends with suitable keys or finger buttons 6. The fingers 3 of bar 2 are slotted as at 7 to permit the insertion of a fulcrum rod 8 and the key-bars 5 are provided with 50 slots 9 to receive said fulcrum-bar when the key-bars are inserted in the slot 4. Each key-bar is provided at its pivoted end with an upwardly projecting arm 10 constituting one member of a toggle-lever,—the other 55 member of said toggle-lever being formed by a type bar 11. The type-bars 11 are arranged

in a straight horizontal line, side by side, and are pivotally supported by a fulcrum-rod 12 passing through said type-bars a comparatively short distance from their upper 60 ends and supported in notches 13 in the fingers 14 of a bar 15,—the type-bars passing through the slots formed by said fingers 14, and in order to prevent displacement of the fulcrum-rod 12, pins 16 may be employed. The lower end of each type-bar 11 is provided with a slot 17 to receive a headed pin 18 on the arm 10 whereby the latter is loosely connected with said type-bar. Each type-bar 11 has rigidly secured to its upper 70 end a type 19 which, when the parts are at rest, is disposed a slight distance from a platen 20. This platen is made in the form of a bar provided at its ends with parallel arms 21 pivotally supported a comparatively 75 short distance forwardly of their rear ends upon a shaft 22 disposed between the sides of the frame 1 and the rear ends of these arms normally rest against the underside of a bar 23 secured to the frame 1 whereby 80 the platen bar 20 will be maintained normally in position. A roller 24 is mounted on the shaft 22 to serve as a paper guide and a paper reel 25 is mounted on suitable supports 26,—the paper from said reel being 85 caused to pass upwardly over the edge of the platen bar 20 and then over the guide roll 24. By pivotally mounting the platen frame, it may be raised to facilitate the threading of the paper. Guides 27 for an 90 inking ribbon 28 are supported by brackets 29 secured to the bar 15 or any convenient part of the framework and this inking ribbon passes between the paper on the edge of the platen bar 20 and the type. 95

The type on the type-bars 11 are maintained normally a slight distance from the inking ribbon and the key-bars are retained and returned to their normal positions by means of springs 30, each of which is attached at one end to a fixed rod 31 and at the other end with the arm 10 of the key-bar slightly above the pivoted end of the latter.

When a key-lever is depressed, the arm 10 on said lever coöperating with the longer arm of the type-bar 11 will cause the upper end of said type-bar to move sufficiently to press the inking ribbon against the paper passing over the platen bar. This slight 110 movement of the type will not cause an appreciable sound in its coöperation with the latter.

platen bar 20, but the force which is applied to the type-bar or lever by reason of the leverage afforded by the connection of the longer arm of the type-bar or lever with the 5 arm 10 on the key-bar, will be sufficient to cause a proper impression to be made by pressure rather than by a blow. In eliminating the hammer action and relying upon pressure to cause the impressions to be made 10 upon the paper, I am enabled to render the operation of the machine practically noiseless, which is a matter of considerable importance in a stenographic typewriting machine.

It will be observed that the type-bars or 15 levers are arranged in a straight horizontal line with the type permanently secured to their upper ends. With such arrangement and construction, proper alinement of the writing will always be maintained without 20 necessity for any adjustment after the parts shall have been once assembled.

An important feature of my improvements is the provision of front-stroke noiseless type-bars so arranged that the writing 25 will appear in a straight line.

Having fully described my invention what I claim as new and desire to secure by Letters-Patent, is,—

1. In a typewriting machine, the combination with a platen, of a series of approximately vertical type-bars having type normally disposed comparatively close to the platen, each of said type-bars pivotally supported between its ends and adapted to 35 have a short stroke toward the platen, and pivotally mounted key-levers, each having a member loosely connected with the lower arm of a type-bar.

2. In a typewriting machine, the combination with a platen, of a series of approximately vertical type-bars or levers, each pivotally supported above its central portion and provided at the end of its shorter arm with a type, and a series of key-levers; each 45 provided with an upwardly projecting member loosely connected at its upper end with

the longer depending arm of the adjacent type-bar or lever.

3. In a typewriting machine, the combination with a platen, of a series of approximately vertical type-bars or levers arranged in a straight horizontal line and provided at their upper ends with type disposed short distances from said platen, means for pivotally supporting said type-bars or levers 55 between their ends, a series of key-levers, each provided with an upwardly projecting member loosely connected at its upper end with the lower end of the adjacent type-bar or lever.

4. In a typewriting machine, the combination with a platen, of a series of approximately vertical type-bars or levers provided with type normally disposed short distances from said platen, means pivotally supporting said type-bars or levers at points below their upper ends, a series of key-levers provided with upwardly projecting members loosely connected at their upper ends with the lower ends of the type-bars or levers, 60 means for supporting said key-levers adjacent to the juncture of the upwardly projecting members therewith, and springs connected with the lower portions of said upwardly projecting members and attached to a fixed support.

5. In a typewriting machine, the combination with a plurality of type-bars arranged side by side in a straight line and carrying type, of a bar platen provided with arms pivotally supported between their ends, and means engaging the free ends of said arms for maintaining the platen normally in a horizontal position in front of the type on the type-bars.

In testimony whereof, I have signed this specification in the presence of two subscribing witnesses.

WARD S. IRELAND.
